UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A CORPORATION OF GREAT BRITAIN.

STEAM TURBINE.

1,412,827.

Specification of Letters Patent. Patented Apr. 18, 1922.

Application filed February 28, 1919. Serial No. 279,747.

To all whom it may concern:

Be it known that I, KARL BAUMANN, a citizen of the Confederation of Switzerland, and a resident of Urmston, in the county of Lancaster, England, have invented a new and useful Improvement in or Relating to Steam Turbines, of which the following is a specification.

This invention relates to steam turbines and more particularly to turbines which are partly or wholly supported in position on their foundations by feet on the ends of the exhaust casing.

Where a steam turbine drives a machine provided with means for ventilating the same during operation, such for example as an alternating current generator with forced ventilation and such machine is located at the exhaust or low pressure end of the turbine, it has hitherto been necessary to provide sufficient space to permit of the duct for supplying air to the machine being located between the exhaust casing of the turbine and said machine, the over-all length of the set being increased by the space needed to accommodate the air duct.

In order that a turbine and a ventilated machine driven thereby may be located in close proximity to one another and the over-all length of the set thereby reduced, the supporting feet or some of them at the end of the exhaust casing of the turbine are, according to the present invention, so constructed that they may also be used as air ducts for the supply of air for ventilating the driven machine.

Several forms in which the invention may be carried into effect are illustrated by way of example in the accompanying drawings in which Figure 1 is a central vertical section of a portion of the rear end of the exhaust casing of a turbine and of the end bell, air trunk and ventilating fan of a dynamo electric machine driven by the turbine, the supporting feet of the turbine being constructed in accordance with this invention. Figure 2 is a half end view of the construction illustrated in Figure 1 with the end bell, fan and air trunk shown in Figure 1 removed. Figure 3 is a similar view to Figure 2 but with the end bell, fan and air trunk shown in Figure 1 in position. Figure 4 is a view similar to Figure 1 shewing a modified construction. Figure 5 is an end view of the same taken on the line

IV—IV of Figure 4. Figure 6 is a view similar to Figure 1 showing another modified construction, Figure 7 being an end view of the constructions shown in Figure 6 with the end bell, air trunk and fan removed. Figure 8 is an end view of a still further constructional form which the invention may take, Figure 9 being a central sectional view of the same taken on the line VIII—VIII of Figure 8 with the end bell and air trunk in position.

In the constructional forms of the invention illustrated in the drawings the turbine is supported in position by feet located at the ends only of the exhaust casing of the turbine. Turbines having supporting feet of this general character are, for example, illustrated in the specification of patent application, Serial No. 187,857, filed 23rd August, 1917.

Referring now to Figures 1, 2 and 3, the rear end of the exhaust casing of the turbine is illustrated at 10, the turbine shaft at 11 and the shaft of the machine driven by the turbine at 12. The supporting feet 13 of the turbine 13 project from the rear wall 10 of the exhaust casing of the turbine and bear on a sole plate 14 resting on the foundations 15 of the plant. The supporting feet include a plurality of projecting webs or ribs 16, 17, 18, the inner ones 17, 18 being of less depth than the outer ribs 16 in order that the end bell 19 of the machine driven by the turbine may approach as closely as possible to the latter. A fan 20 mounted on the shaft 12 draws air for ventilating the machine driven by the turbine through channels provided in the sole plate 14 as shown by the arrows between the ribs 16 and 17, 17 and 18 of the supporting feet 13 and thence through an air trunk 21 attached to the end bell 19 and connecting with the upper ends of the supporting feet 13 as shown. The machine driven by the turbine is here indicated as a dynamo electric machine, the position occupied by the yoke of which is indicated by the dotted lines in Figures 2 and 3.

In Figures 4 and 5 a portion 22 of the lower part of the end bell 19 is formed integral with the supporting feet 13 of the turbine, the inner ribs or webs of the feet 17, 18 being extended lengthwise towards the driven machine at their upper ends and joined by a transverse curved web 23 having

a machined face 24 on its lower edge to which the other portion 25 of the lower part of the end bell is secured by bolts. In other respects the construction does not differ materially from that illustrated in Figures 1 to 3.

The construction illustrated in Figures 6 and 7 permits of the machine driven by the turbine being located still nearer the turbine itself. In this construction the air for ventilating the machine is caused to pass between the ribs forming the supporting feet of the turbine across the rear wall of the exhaust casing of the turbine 10, the air entering the turbine feet from a wind trunk 26 located between the foundations 15 and the shell 27 of the condenser which is here shown bolted direct to the exhaust casing 10 of the turbine. A transverse wall 28 connects the ribs 16, 17 and 18 of the feet to form a ventilating channel. The upper ends of the ribs where they adjoin the exhaust casing 10 are extended outwardly, as shewn at 29, to form a support for the air trunk 21, attached to the exterior of the end bell 19.

The construction shewn in Figures 8 and 9 is very similar to that illustrated in Figures 6 and 7 with the exception that the air trunk 21 is considerably reduced in height and is provided with an internal guide wall 30 located at its upper end for directing the in-flowing air into the aperture in the end bell 19. In Figure 8 the upper end of the rib 17 of the supporting feet 13 is curved as shewn at 31 for the purpose of directing the flow of the ventilating air into the fan 20. In this construction the upper end of the transverse wall 28 is provided with a machined face 29 to which a corresponding face formed on the lower portion of the end bell 19 is bolted.

In the construction shewn in Figures 6 to 9 in which the air passes over the end wall of the exhaust casing of the turbine the latter is preferably provided with sheet lagging so that the air passing through the ducts or channels will not become unduly heated before entering the machine driven by the turbine.

I claim as my invention:

1. In a turbine installation, the combination of an exhaust casing, supporting means for the exhaust casing, a driven element requiring cooling medium arranged adjacent to said casing, and cooling medium passages provided in the supporting means for supplying cooling medium to the driven element.
2. In a turbine installation, the combination of an exhaust casing, supporting means for the casing, a driven mechanism having an enclosing casing and requiring cooling medium, passageways in the supporting means for supplying a cooling medium, and

a chamber or trunk communicating with the passageways and with the interior of said enclosing casing.

3. In a turbine installation, the combination of an exhaust casing, a dynamo-electric machine arranged close to the exhaust casing, supporting feet for the exhaust casing, and air passages in the feet for supplying cooling air to the dynamo-electric machine.

4. In a turbine installation, the combination of an exhaust casing, a dynamo-electric machine arranged close to the exhaust casing, supporting feet for the exhaust casing, air passages formed in the feet and communicating with the interior of said dynamo-electric machine, and means carried by a rotatable element of said machine for inducing a circulation of cooling air.

5. In a turbine installation, the combination of an exhaust casing, a dynamo-electric machine arranged close to the exhaust casing, supporting feet for the exhaust casing, air passages in the supporting feet, and an air trunk or chamber communicating with said passages and with the interior of said machine.

6. In a turbine installation, the combination of an exhaust casing, a dynamo-electric machine arranged close to the exhaust casing and having an end bell, supporting feet for the exhaust casing and air passages formed in the feet and communicating with the interior of said end bell.

7. In a turbine installation, the combination of an exhaust casing, a dynamo-electric machine arranged close to the exhaust casing and having an end bell, supporting feet for the exhaust casing, air passages formed in the supporting feet, and a trunk or chamber carried by the end bell and affording communication between the passages and the interior of said end bell.

8. In a turbine installation, the combination of an exhaust casing, a dynamo-electric machine arranged close to the exhaust casing and having an end bell, supporting feet for the exhaust casing, air passages formed in the supporting feet, a trunk or chamber carried by the end bell and affording communication between the passages and the interior of said end bell, and means carried by an element of said dynamo-electric machine for inducing a circulation of air.

9. In a turbine installation, the combination of an exhaust casing, a dynamo-electric machine arranged close to the exhaust casing and having an end bell provided with a shaft aperture, supporting feet for the exhaust casing, air passages provided in the supporting feet, a trunk or chamber on the end bell communicating with the passages and with the shaft aperture and guide means in the trunk or chamber for directing air toward the shaft aperture.

10. In a turbine installation, the combina-

tion of an exhaust casing, a dynamo-electric machine having an end bell arranged close to the exhaust casing, supporting feet for the exhaust casing having ribs, means cooperating with the ribs to define air passages, and means for affording communication between the passages and the interior of said end bell.

11. In a turbine installation, the combination of an exhaust casing, a dynamo-electric machine having an end bell arranged close to the exhaust casing, supporting feet for the exhaust casing having ribs, means cooperating with the ribs to define air passages, an air trunk or chamber carried by the end bell for affording communication between the passages and the interior of said end bell.

12. In a turbine installation, the combination of an exhaust casing, a dynamo-electric machine arranged close to the exhaust casing, supporting feet for the exhaust casing having vertical ribs, means cooperating with the ribs to define air passages, a trunk or chamber communicating with the passages and with the interior of the end bell for supplying cooling air to the latter.

13. In a turbine installation, the combina-

tion of an exhaust casing, a dynamo-electric machine arranged close to the exhaust casing and having an end bell, supporting feet for the exhaust casing having vertical ribs, means cooperating with the ribs to define air passages, a trunk or chamber communicating with the passages and with the interior of the end bell for supplying cooling air to the end bell and means arranged within the end bell for inducing a circulation of cooling air.

14. A turbine-driven electric unit comprising a dynamo-electric machine, a turbine having supporting feet provided with air passages and having a portion shaped to constitute a part of the electric machine end-casing, a casing element cooperating with said casing portion of the feet, and a second element cooperating with the first element to constitute a passageway for air in communication with the passages of the feet and with the interior of the casing.

In testimony whereof I have hereunto subscribed my name this tenth day of January, 1919.

KARL BAUMANN.
